H. A. DOUGLAS

ELECTRIC SWITCH

Filed July 23, 1924

Inventor:

Harry A. Douglas

By G. L. Clegg Atty.

UNITED STATES PATENT OFFICE.

HARRY A. DOUGLAS, OF BRONSON, MICHIGAN.

ELECTRIC SWITCH.

Application filed July 23, 1924. Serial No. 727,725.

To all whom it may concern:

Be it known that I, HARRY A. DOUGLAS, a citizen of the United States, residing at Bronson, in the county of Branch and the 5 State of Michigan, have invented a certain new and useful Improvement in Electric Switches, of which the following is a full, clear, concise, and exact description.

My invention relates to electric switches 10 of the push and pull type and has for its object the provision of improved assembly of component parts of such a switch, an improvement in the switch mechanism and an improvement in the switch operating 15 means. The switch of my invention, in one aspect, includes two contacts, a contact member common to said contacts and engageable with both of them at the same time, and a reciprocable rod in actuating 20 relation with said contact member.

The reciprocable rod is guided by a flanged member which, with the switching parts, is enclosed by a casing. This casing includes two assembled plates between 25 which the flange of the flanged member is clamped. In accordance with another characteristic of the invention, the switch includes a sinuously formed support for one of the contact members to furnish a hump 30 which is engageable by the reciprocable rod to operate the switch member carried upon the support.

The invention will be more fully explained in connection with the accompanying 35 drawing in which Fig. 1 is a longitudinal sectional view of the switch as it is preferably constructed; Fig. 2 is a sectional view on line 2—2 of Fig. 1; Fig. 3 is a sectional view taken at right angles to the direction in which Fig. 2 is taken; Fig. 4 is an end view with parts broken away; Fig. 5 is a side view with portions broken away; Fig. 6 is a sectional view on line 6—6 of Fig. 1 and Fig. 7 is a perspective view of 45 one of the switch contact members and a carrier for this member.

The switch illustrated is provided with an enclosing casing having a cup shaped portion 1 and a hollow stem continuation 2 of this cup, this stem being threaded to receive the clamping nuts 3 and 4 between which the support 5 for the switch may be clamped. Insulating plates 6 and 7 close the cup 1. These plates are assembled by 55 hollow rivets 8 having flanged ends 9 and

10 between which the plates are clamped. These rivets are interiorly threaded to receive the binding screws 11 whose heads clamp the conductors 12 and 13 against the rivet heads 9. The cup is formed with inwardly extending tongues 14 that are turned over plate 7 whereby the two plates, the rivets and the parts associated with these rivets are assembled with the cup. The plate 6 has openings 15 which receive the tongues. The inner heads 10 of the rivets constitute the terminal contacts or members of the conductors 12 and 13. A contact member 16 is common to the contacts 10, being engageable with both of these contacts simultaneously and separable therefrom according to the adjustment of the contact member 16. When the contacts 10 are engaged by the contact member 16 common thereto, the rivets are electrically connected to electrically connect the conductors 12 and 13. The contact member 16 is preferably inwardly formed from a strip of spring metal with a carrier 17, which is quadrilaterally shaped, generally speaking. The end of the carrier 17 that is opposite the contact member 16 is bent over the plate 7 and has a tongue 18 which is receivable within an opening 19 formed in the plate 7. The thickness of this plate is slightly reduced to afford a space between the plates 6 and 7 between which the adjacent portion of the carrier 17 is received and clamped.

A rod 20 passes through the bowl of the stem 2, this rod having a head 21 by which it may be reciprocated. This rod telescopically receives a pin 22 at its inner end, the rod sliding upon the pin as the rod is moved in and out. The pin or member 22 is formed with a flanged head 23 which is received within a recess in the plate 7 and which is clamped between this plate and the complementary plate 6. The plates thus serve to support the rod 20 and the pin 22 at the switch end of the structure, the stem 2 being contracted at its outer end to support the outer end of the rod. A disc of insulation is carried upon the inner end of the rod 20 and, virtually, constitutes a lateral extension of this rod, which is in actuating relation with the switch member 16, whereby this member is moved away from the contacts 10 when the rod 20 is adjusted to force the disc 24 into

2

actuating relation with the switch member, this switch member being free to engage the contacts 10 when the disc 24 is moved out of actuating relation with the switch member. In the preferred embodiment of the invention, the disc 24 operates the switch member 16 through the intermediation of the carrier 17 for this switch member. To this end the side of the carrier 17 which is adjacent the switch member 16, is desirably of sinuous form affording a hump 25 with which the disc 24 is engaged when the switch member 16 is to be brought out of circuit closing relation. As shown, there are spaces 26 upon each side of this hump in which the disc is received when the plunger is innermost and outermost. When the disc 24 is innermost, it engages the contacts 10 and is thereby held in a position in which it will engage the left hand side of the hump 25 (Fig. 1), to hold the contact member 16 out of engagement with the contacts 10, the left hand space 26 then receiving the disc 24 sufficiently to enable the hump 25 to hold the disc in its innermost position to maintain the switch open. When the disc 24 is outermost, it will sufficiently enter the right hand space 26 to permit the contact member 16 to engage the contacts 10, due to the resilience of the carrier 17. When so engaged, practically all of the current flowing between the contacts 10 passes through the member 16 without materially traversing the carrier 17. To prevent the carrier from having contact with the hollow stem 2 in case the disc is moved too far outwardly, I surround the rod 20 with a floating insulating washer 27 which is interposed between the inner end of the stem 2 and the carrier 17 for the purpose stated.

Changes may be made without departing from my invention.

Having thus described my invention, I claim:—

1. In an electric switch, the combination with two contacts; of a contact member common to said contacts and engageable with both of them at the same time; a carrier for said contact member having a sinuous portion; and a reciprocable rod engageable with a hump of said sinuous portion to actuate the carrier. 45

2. In an electric switch, the combination with two contacts; of a contact member common to said contacts and engageable with both of them at the same time; a carrier for said contact member having a sinuous portion and integrally formed therewith out of one piece of metal; and a reciprocable rod engageable with a hump of said 50 sinuous portion to actuate the carrier. 55

3. In an electric switch, the combination with a contact; of a contact member complementary to said contact; a carrier for said contact member having a sinuous portion; and a reciprocable rod engageable with a hump of said sinuous portion to actuate the carrier. 65

4. In an electric switch, the combination with a contact; of a contact member complementary to said contact; a carrier for said contact member having a sinuous portion and integrally formed therewith out of one piece of metal; and a reciprocable rod engageable with a hump of said sinuous portion to actuate the carrier. 70 75

In witness whereof, I hereunto subscribe my name.

HARRY A. DOUGLAS.
